UNITED STATES PATENT OFFICE.

OTIS W. STANFORD, OF LEBANON, OHIO, ASSIGNOR TO HIMSELF AND
ROBERT W. GILCHRIST, OF SAME PLACE.

GRAIN-SEPARATOR.

Specification forming part of Letters Patent No. 43,817, dated August 9, 1864.

To all whom it may concern:

Be it known that I, OTIS W. STANFORD, of Lebanon, Warren county, Ohio, have invented a new and useful Improvement in Separators; and I do hereby declare the following to be a full, clear, and exact description thereof, reference being had to the accompanying drawings, making part of this specification.

Figure 1 is a perspective view of a machine embodying my improvements, the fan-case being removed. Fig. 2 is a longitudinal section of the machine. Fig. 3 is a transverse section of the shoe, showing the side ducts for the grass-seed. Figs. 4 and 5 are enlarged views of details.

A represents the frame and casing, and C the fan. The casing being entirely omitted opposite the sides of the shoe B enables the latter to be substantially of the same width as the fan-case, so as to afford the greatest possible working capacity within given dimensions. The hopper D has a sliding cut-off, E, which can be set more or less open by means of a notched rod, F, which, extending from the bottom of the cut-off board, engages over a catch, f. The part of the shoe B immediately beneath the hopper has a chute G, from which a series of fingers, H, project laterally above the upper surface of the chute and rearward beyond its edge. The fingers H, thus elevated above the chute, preserve the latter from the direct contact of the chaff and facilitate the separation of the seeds, which, falling upon and rolling down the chute, are conducted by the latter and by the fingers H onto a screen I, through which the clover and grass seeds drop onto a double inclined chute, J, whence they are conducted by two ducts, K K', in the shoe sides into a grass-seed box or drawer. The shoe B is near its mid-height and rear end suspended to the casing by means of yielding steel or iron bars attached at or above their middles to opposite sides of the shoe and secured vertically to the casing by their extreme ends. One of these bars is seen at L, Fig. 1. This mode of suspending the rear end of the shoe together with the presently described single center of suspension at

the upper front edge of the shoe enable a peculiar vertical and lateral agitation of the latter. The front upper part of the shoe at its mid-width rests upon a pallet, P, whose upper and lower extremities occupy, respectively, notches in the shoe and in a bridge, Q, which depends from the frame.

The lateral agitation or rocking of the shoe is effected as follows: The drum shaft M carries a zigzag cam, N, which, working in a yoke, O, which projects from the front side of the shoe, imparts to the latter a peculiar complex swaying and rocking motion upon its three centers or points of suspension.

In addition to the above lateral rocking motion an abrupt vertical jar is imparted to the front part of the shoe by providing the pallet P with two arms, p p', which act to strike a projection from the shoe at each lateral agitation of the latter. In order to enable an adjustment of the force of this vertical blow or jar, I provide a plate or bracket, R, having two oblique slots, r r', and two set-screws, r' r''. The setting of this plate lower down or higher up causes the pallet to strike with a greater or less force.

S represents grooves for several sorts and conditions of screens.

T represents a yielding catch or bar by which any number of screens may be held to whatever grooves they may be placed in.

In order to secure stability on uneven floors, the machine is made to stand on three feet, U U' U'', of which the two former support the two front corners of the machine, while the latter supports the rear end of the machine at its mid-width.

I claim herein as new and of my invention—

1. The arrangement of the shoe B, suspended near mid-height at its rear end in the open-sided frame or casing A by means of the yielding side straps or bars, L, and poised in front upon the single pallet P p p', whose arms act to strike the shoe when the latter is laterally agitated by the zigzag cam N, or its equivalent, substantially as set forth.

2. The arrangement immediately beneath the discharging-aperture of the hopper of

the chute G, from which a series of fingers, H, project above the upper surface of the chute and rearward beyond its edge, for the purposes set forth.

3. The arrangement of grass seed screen I, double inclined chute, J and side ducts, K K', substantially as set forth.

4. The provision of the spring bar or catch

T, for the secure holding and ready liberation of one or more screens, as set forth.

In testimony of which invention I hereunto set my hand.

OTIS W. STANFORD.
